WEDGE ADJUSTING MECHANISM

Lloyd N. Hutchinson, New York, N. Y., and
 George H. Zouck, Orange, N. J., assignors to
 Franklin Railway Supply Company, New York,
 N. Y., a corporation of Delaware

Application March 23, 1935, Serial No. 12,626

12 Claims. (Cl. 105—81)

This invention relates to mechanism for adjusting the wedges commonly used in locomotive driving boxes and is particularly concerned with certain improvements designed to give better control of the spring action so as to avoid danger of the wedge sticking in position, to minimize shocks to and breakage of the various parts, to reduce the overall height of the adjusting mechanism, to reduce fatigue upon and therefore to 10 increase the life of each of the springs, to better distribute the thrusts in order to avoid canting and binding of the parts, to render proper adjustment more readily possible, to provide for ready visual inspection of the parts as a guide 15 to proper adjustment and in general to simplify and improve mechanism of this character and lessen the cost of its maintenance.

The accompanying drawings illustrate a preferred embodiment of the invention, wherein—
 20 Figure 1 is a vertical central section through our improved construction with a portion of a locomotive driving axle and driving box also shown in section but with the pedestal jaw and binder shown in side elevation.

Figure 2 is a section on the line 2—2 of Figure 1.

Figure 3 is a section through our improved construction similar to that of Figure 1 but illustrating only the adjusting mechanism proper on an enlarged scale, and

Figure 4 is a perspective view of the improved seat ring used in our invention.

Referring to the drawings, it will be seen that the locomotive driving axle 5 is mounted as usual in a driving box 6. The pedestal jaw 8 is formed with its inside face 9 inclined downwardly and outwardly away from the adjacent face of the driving box in a manner familiar to those skilled in this art, and between this inclined face 9 and the driving box is located a parallel-sided liner or wear plate 10 and a wedge or compensator 11 having flanges 17 for embracing the pedestal jaw 8 and to the bottom of which is secured a wedge bolt 12 extending downwardly through an opening 13 in the pedestal binder 14. The wedge bolt is free to move upwardly and downwardly in the opening 13 and its lower end is threaded as at 15.

Below the pedestal binder is a main supporting bracket having a depending cylindrical cup-shaped pocket portion 16, the securing flanges 17 and 18 and the reinforcing ribs 19. The flanges 17 and 18 are suitably apertured for reception of the holding bolt 20 and a binder bolt 21 which serve to hold the supporting bracket 55 in position against the under face of the binder.

At the top or mouth of the cylindrical cup-shaped portion 16 is a pair of oppositely disposed recessed shouldered portions 22 which project outwardly from the cup-shaped portion 16. The outer walls of these recessed shoulder portions are provided with peep-holes 23 through which inspection of the parts is readily made for the purpose of ensuring proper adjustment as will further appear. Additional peep-holes 23a are provided lower down and on the opposite sides of 10 the pocket 16.

The bottom of the cylindrical cup-shaped portion 16 is provided with an inwardly extending flange 24 having a central aperture 25. Within the cup-shaped portion 16 and resting upon the flange 24 is a main or snubbing spring 26. This spring as shown is a coil spring and is concentrically arranged with respect to the cup 16 as well as with respect to the threaded end 15 of the wedge bolt 12. The upper end of the spring 20 26 extends slightly above the recessed shoulder portions 22.

Within and concentric to the spring 26 is a secondary or supplementary spring housing 27 also of cup-shape and having an inwardly extending flange 28 at the bottom with a recess 29 therethrough and an outwardly extending flange 30 at the top which projects over the adjacent end of the spring 26 and into the recessed shouldered portions 22. The flange 30 is adapted to 30 rest on the top of the spring 26 which holds it slightly above the shouldered portions 22 as clearly shown to particular advantage in Figure 3.

Projecting upwardly from the upper face of the flange 30 is a pair of oppositely disposed stop walls or projections 31 spaced apart so as to provide passages in line with the shouldered recesses 22. The walls 31 are provided with upwardly tapering widened portions 32 at the sides of the 40 spaces therebetween, as shown probably to best advantage in Figure 2. These serve to strengthen the wall at this point and as shown the adjacent portions 32 at each side are arranged to fit into the widened portions 33 of the shouldered 45 recesses 22. The interior faces of the walls 31 are cored out as at 34.

The stop walls 31 with their enlarged portions 32 serve to limit the extent to which the spring 26 can expand by virtue of the fact that they bear 50 against the under face of the pedestal binder 14 as clearly shown in Figure 1. The force of the spring 26, therefore, is, as it were, "locked up" until such time as an unusual downward thrust of the wedge takes place, as will appear more 55

clearly hereinafter in connection with the brief description of the operation of the device.

Within the cup-shaped portion of the housing 27 is a second coiled spring 35 concentric to the cup as well as to the other spring, the pocket 16 and the wedge bolt 12. This spring is of considerably lighter character than the main or snubbing spring and is known as the compensating and adjusting spring. It rests on the flange 28 and projects slightly above the flange 30 in position to support the seat ring 36 now to be described.

The seat ring is essentially a washer, although, for the sake of adjustment, where that may be necessary, additional washers 37 of ordinary type and smaller diameter may be introduced between the top of the spring and the under face of the seat ring. At oppositely disposed points the seat ring carries the axially projecting positioning lugs 20 38 which extend between the walls 31 and into the shouldered recesses 22 so that the lugs 38 serve to prevent rotation of the seat ring by virtue of their engagement with the side walls of the recesses 22. On one face the lugs 38 are provided 25 with extensions 39 for a purpose which will appear more clearly below. Both faces of the seat ring are radially grooved as at 40 in order to provide surfaces which engage with correspondingly projecting and similarly disposed surfaces on the 30 under face of the adjusting nut as will further appear.

The wedge adjusting nut 41 comprises an upper or head portion having the flange 42 adapted to extend over the adjacent face of the seat ring and 35 a lower or sleeve-like shank portion 43 which projects downwardly concentric to and through the interior of the several springs and cups and outwardly through the openings 29 and 25 in the bottoms of the two cups. The lower end may be 40 suitably squared or hexagoned as at 44 in order to receive a wrench by means of which the nut can be rotated upon the threads 15 in order to make the necessary adjustment of the spring 35. The under surface of the flange 42 is provided 45 with radially extending projecting portions 45 which are adapted to interfit with the grooves 40 in the seat ring in order to prevent unintentional turning of the nut. Adjustment, however, can be effected by forcibly rotating the nut by means of 50 the wrench, such rotation simply depressing the seat ring slightly in order to free the interengaging tongues and grooves. In normal operation, however, such rotation will not take place so that when once adjusted the parts will remain 55 in adjusted position.

It will be noticed that the seat ring 36 is shown in Figure 1 with the projecting portions 39 on the lugs 38 extending upwardly toward the under face of the binder 14, while in Figure 3 the projections 39 extend downwardly toward the adjacent face of the flange 30 on the spring housing 27. It will, therefore, be obvious that by a mere reversal of the seat ring 36 two different adjustments are possible—the position in Figure 65 1 being such as will make possible a greater compression of the spring 35 while the position shown in Figure 3 will produce a less compression on the spring 35, the reason for this being that it is always the intention to have an approximately 70 constant clearance between the upper face of the flange 30 and the under face of the seat ring. We prefer to have this space approximately three-eighths of an inch which we have found for all ordinary conditions of operation is the proper 75 spacing to take care of the normal movements

of the wedge as well as to allow for expansion of the parts as they heat up in service. If a still greater tension is desired than would be possible with the seat ring in either one of its positions, one or more additional washers 37 of ordinary type may be inserted between the top of the spring 35 and the adjacent face of the seat ring.

It should also be noted that the projections 39 may be reduced if necessary, in order to make the requisite initial adjustment of the spring 35 and 10 still leave the required operating space between the flange 30 and the seat ring.

The construction just above described is of great importance in making the device adaptable to a wide range of installation because we have 15 found from much experience that there is considerable variety of conditions either of size or of wear which make it necessary to provide some means for properly adjusting the inner spring 35 for each individual installation. With devices 20 heretofore in use where these various adjustment features have not been provided it has frequently been necessary, in order to install a device of this kind on locomotives of different characteristics, either to supply springs of different initial tension or to change the height of those furnished by raising or lowering the seat ring which, in turn, will, of course, increase or decrease the desired standard spacing of approximately three-eighths inches which we wish to maintain between the seat ring and the flange 30.

It will, therefore, be seen that our improvements make possible a very wide range of adjustment without the necessity of using more than one set of parts and without the necessity 35 of varying the desired standard of spacing between the flange 30 and the adjacent face of the seat ring.

As stated, the inner spring takes care of all 40 normal thrusts and also of expansion and contraction of the parts due to heating in service. However, when abnormal thrusts come into play such, for example, as may be encountered when the driving wheels pass over a switch or a crossover or should a section of uneven track be encountered, or in the event of an unusually heavy piston thrust, the main or snubbing spring 26 will come into play automatically in order to carry this additional load, although for all normal operation the snubbing spring 26 plays no 45 part in the adjustment of the wedge or compensator.

It will also be noted that the two springs 50 always act independently of each other because after the inner compensating spring 35 is compressed to its full extent no further compression can take place during the time that the outer or snubbing spring is compressed for the reason that the seat ring is positively limited in its motion by virtue of the fact that it comes into contact with the flange 30 on the inner housing 27. This arrangement is of added importance because it makes possible a shortening of the overall height of the device. In previous devices 55 both of the springs rested upon the bottom flange 24 of the outer pocket 16, so that at the time that the snubbing spring came into play the inner or compensating spring was still further compressed, thereby increasing its pressure and adding it to the pressure of the snubbing spring. With an arrangement of this kind it is necessary 60 to make the inner or compensating spring of greater length than is required with our improved arrangement disclosed herein. This decrease in height is of extreme importance in 65 70 75 75

many locomotives where the clearance between the binder and the rail is limited.

Our improved device ensures more positive control of the wedge and prevents jamming thereof and by virtue of the fact that it operates more satisfactorily and uniformly than previous wedge mechanisms it reduces to a large extent the constant upward and downward vibration of the springs due to the reciprocation of the engine pistons and in this way materially reduces the fatigue upon the springs as well as the shocks upon the parts, so that the life of the equipment is greatly extended. The concentric arrangement of the parts prevents canting and binding which, if it occurred, would, of course, interfere with the proper automatic adjustment of the wedge.

What we claim is:

1. Wedge adjusting mechanism including in combination with a wedge bolt which passes downwardly through an opening in a pedestal binder, a cup-shaped supporting bracket, a coiled spring concentrically supported in said cup-shaped bracket, a second coiled spring concentric to said first spring, a support for the second spring resting on the first spring and having stop means for engaging the under face of the binder to limit the movement of said first spring, and a nut threaded on the bolt concentrically of said springs and their supports and adapted to be carried by said second spring.

2. Wedge adjusting mechanism including in combination with a wedge bolt which passes downwardly through an opening in a pedestal binder, a cup-shaped supporting bracket, a coiled spring concentrically supported in said cup-shaped bracket, a second coiled spring concentric to said first spring, a cup-shaped housing for the second spring concentric to the first spring, which housing has a flange resting on the first spring and also having stop means for engaging the under face of the binder to limit the movement of said first spring, a seat ring resting on the second spring, and an adjusting nut threaded on the bolt and resting on said seat ring.

3. Wedge adjusting mechanism including in combination with the wedge bolt, a cup-shaped supporting bracket, a coiled spring concentrically supported in said cup-shaped bracket, a second coiled spring concentric to said first spring, a cup-shaped housing for the second spring concentric to the first spring, which housing has a flange resting on the first spring, a seat ring resting on the second spring, and an adjusting nut threaded on the bolt and resting on said seat ring, there being interlocking means between the nut and the seat ring and the nut having a sleeve which projects downwardly through openings in the housing and in the bracket.

4. Wedge adjusting mechanism including in combination with the wedge bolt, a supporting bracket, a snubbing spring carried by the bracket and surrounding the bolt, a cup-shaped housing within the snubbing spring having a flange which rests on said spring, a compensating spring in said cup-shaped housing also surrounding the bolt, an adjusting nut threaded onto the bolt and having a sleeve which projects downwardly through openings in the housing and in the bracket, and a seat ring between the nut and the compensating spring, said seat ring, under normal operating conditions, being supported on the compensating spring clear of the flange on said housing but being adapted to seat on the flange

during abnormal downward thrusts of the wedge and its bolt.

5. Wedge adjusting mechanism including in combination with the wedge bolt, a cup-shaped supporting bracket, a coiled spring concentrically supported in said cup-shaped bracket, a second coiled spring concentric to said first spring, a cup-shaped housing for the second spring concentric to the first spring, which housing has a flange resting on the first spring, spaced stop members projecting upwardly from said flange to limit the action of the first mentioned coiled spring, a seat ring resting on the second mentioned spring, positioning lugs projecting radially from the seat ring through the spaces between the stop members, and an adjusting nut threaded on the bolt and resting on said seat ring.

6. Wedge adjusting mechanism including in combination with the wedge bolt, a cup-shaped supporting bracket, a coiled spring concentrically supported in said cup-shaped bracket, a second coiled spring concentric to said first spring, a cup-shaped housing for the second spring concentric to the first spring, which housing has a flange resting on the first spring, spaced stop members projecting upwardly from said flange to limit the action of the first mentioned coiled spring, a seat ring resting on the second mentioned spring, positioning lugs projecting radially from the seat ring through the spaces between the stop members, and an adjusting nut threaded on the bolt and resting on said seat ring, there being interlocking means between the nut and the seat ring.

7. Wedge adjusting mechanism including in combination with a wedge bolt which passes downwardly through an opening in a pedestal binder, a supporting bracket surrounding the bolt and secured to the under face of the binder, a snubbing spring surrounding the bolt and carried by the bracket, a spring housing resting on the snubbing spring, a second spring of lesser tension carried in said housing, a nut threaded on the bolt for adjusting said second spring, and stops on the spring housing extending upwardly to abut against the binder in order to prevent the snubbing spring from acting on the wedge bolt until after compression of the second spring.

8. Wedge adjusting mechanism including in combination with a wedge bolt which passes downwardly through an opening in a pedestal binder, a cup-shaped supporting bracket secured to the binder, a snubbing spring carried in the cup-shaped portion of the bracket, said bracket having recessed shoulder portions projecting outwardly from the region of the upper end of the snubbing spring, a spring housing within said snubbing spring, said housing having flanges projecting outwardly over the snubbing spring and into said recessed shoulder portions and being supported, under normal operating conditions, by said snubbing spring clear of the shoulder portions, a second spring of lesser tension carried in said housing, a seat ring having positioning lugs also projecting into said recessed portions, said seat ring, under normal operating conditions, being carried by the second spring with its positioning lugs clear of the housing flanges and a nut threaded on the bolt for adjusting the tension of the second spring by movement of the seat ring, said second spring acting independently of the snubbing spring until after the seat ring is forced against the housing flanges, and said shoulder portions thereafter limiting compression of the snubbing spring.

9. Wedge adjusting mechanism including in combination with a wedge bolt which passes downwardly through an opening in a pedestal binder, a cup-shaped supporting bracket secured 5 to the binder, a snubbing spring carried in the cup-shaped portion of the bracket, said bracket having recessed shoulder portions projecting outwardly from the region of the upper end of the snubbing spring, a spring housing within said 10 snubbing spring, said housing having flanges projecting outwardly over the snubbing spring and into said recessed shoulder portions and being supported, under normal operating conditions, by said snubbing spring clear of the shoulder portions, a second spring of lesser tension carried in 15 said housing, a seat ring having positioning lugs also projecting into said recessed portions, said seat ring, under normal operating conditions, being carried by the second spring with its positioning lugs clear of the housing flanges and a nut threaded on the bolt for adjusting the tension of the second spring by movement of the seat ring, said second spring acting independently of the snubbing spring until after the seat ring is forced 20 against the housing flanges, and said shoulder portions thereafter limiting compression of the 25

snubbing spring and there being peep-holes in the outer walls of the recessed shoulder portions.

10. An invertible seat ring or lock washer for a wedge adjusting mechanism of the character described having wedge nut engaging surfaces on both of its faces and a reducible adjustment extension projecting axially beyond the plane of one of its faces. 5

11. An invertible seat ring or lock washer for a wedge adjusting mechanism of the character 10 described having radially projecting positioning lugs, wedge nut engaging surfaces on both of its faces and reducible adjustment extensions projecting axially from one face of the positioning lugs. 15

12. A cup-shaped housing for the compensating and adjusting spring of a wedge adjusting mechanism of the character described, said housing having an outwardly projecting spring engaging flange at the mouth of the cup, a positioning abutment projecting axially from said flange and a central aperture in the base of the cup for passage of a wedge adjusting part. 20
